CLAIM

I claim the ornamental design for a universal wheel knuckle for vehicle, as shown and described.

DESCRIPTION

FIG. 1 is a top right perspective view of a first mode of a universal wheel knuckle for vehicle showing my new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a top left perspective view of a second mode of a universal wheel knuckle for vehicle showing my new design;

FIG. 9 is a left side elevation view thereof;

FIG. 10 is a front elevation view thereof;

FIG. 11 is a rear elevation view thereof;

FIG. 12 is a top plan view thereof;

FIG. 13 is a bottom plan view thereof; and,

FIG. 14 is a right side elevation view thereof.
